UNITED STATES PATENT OFFICE.

ROBERT LELAND KINCAID, OF SYRACUSE, NEW YORK.

WASHING MACHINE.

Application filed April 30, 1920. Serial No. 377,945.

To all whom it may concern:

Be it known that I, ROBERT LELAND KINCAID, a citizen of the United States, and a resident of Syracuse, in the county of Onondaga and State of New York, have invented a certain new and useful Washing Machine, of which the following is a specification.

This invention relates to washing machines and has for its object a machine which is particularly simple in construction, economical in manufacture, and highly efficient, rapid and durable in use, and also which embodies in one structure without complex parts, the vacuum principle of some washing machines, and the sloshing or waterfall principle of other machines. The invention consists in the novel features and in the combinations and constructions hereinafter set forth and claimed.

20 In describing this invention, reference is had to the accompanying drawings in which like characters designate corresponding parts in all the views.

Figure 1 is a plan view, partly broken away, of a washing machine embodying my invention.

Figure 2 is a vertical sectional view.

Figure 3 is a detail view of the means for holding the clothes receptacle elevated.

30 Figure 4 is an enlarged fragmentary view of the connection between the actuating mechanism and the rocking receptacle.

Figure 5 is an enlarged detail view on line 5—5, Fig. 4.

35 This washing machine comprises, generally, a tub, means in the tub to support the clothes or other articles to be washed, and to lift the cleansing fluid or water from the bottom of the tub below the clothes and discharge it onto the clothes and in so doing create a partial vacuum in the bottom of the tub which draws the cleansing fluid or water through the clothes, and mechanism for actuating said means.

45 1 designates the tub which may be of any suitable form, size and construction, it being here shown as rectangular in plan and as having a cylindric concave bottom 2. The tub is supported on a suitable frame 3 and is provided with a suitable cover 4. The means for supporting the clothes is here shown as a receptacle 5 supported in the tub to move or oscillate about an axis substantially coaxial with the cylindric bottom 55 of the tub, the receptacle having a cylindric

bottom 6 concentric with, and spaced apart from, the bottom 2 of the tub, and having openings or passages for the fluid. These openings are perforations 7 in the slats or boards forming the bottom but may be provided by spacing said slats apart.

The receptacle 5 is provided with axles or studs 8 at its ends which are journaled in bearings 9 normally resting in seats 10 provided in blocks 11 resting on angle irons 11^a secured to the inner faces of the end walls of the tub. The bearings 9 are provided at the lower ends of links 12 forming part of the mechanism to be presently described, for lifting the receptacle 5 out of its normal position. The heads or end walls 13 of the receptacle 5 are higher than the top edges of the cylindric bottom 6, and the edges 14 thereof incline upwardly and inwardly from the edge of the cylindric bottom 6 to provide clearance for rocking movement of the receptacle. The central part of the top edges of said heads incline downwardly at 15 toward the axis of the receptacle. Top pieces or boards 16 are secured to the heads 13 at the edges of the cylindric bottom 6 to hold the clothes from tumbling out during the oscillation of receptacle. Also braces as slats 17 connect the end walls or heads of the receptacle.

85 The means for discharging or lifting the fluid or water from the bottom of the tub and discharging it into the receptacle 5, as here illustrated, comprises blades or paddles 18 projecting from the receptacle 5 into the space between the receptacle and the bottom of the tub, these blades being preferably rigid with the receptacle and located on opposite sides of the axis of the receptacle and usually near the upper edges of the cylindric bottom 6 thereof, and running at their free edges close to the inner face of the cylindric bottom 2 of the tub 1. During oscillation of the receptacle the blade 18 moving upwardly lifts the fluid and discharges it over the boards 16 and into the receptacle or on the clothes therein. During this movement the other blade 18 is moving downwardly under the fluid into position to lift the fluid when the direction of movement of the receptacle is reversed. The blades cause a partial vacuum under the receptacle, which draws the fluid so discharged on the clothes, through the clothes back into the bottom of the tub. For in-

creasing the downward suction through the receptacle a partition or baffle plate 19 may be provided on the bottom of the tub between the paths swept by the blades 18, 5 this baffle plate terminating near the bottom of the receptacle. The baffle plate 19 may however, be dispensed with.

The blades 18 during their downward movement force the water before them causing it to surge through the perforations in 10 the bottom of the receptacle 5.

The actuating means may be of any suitable form, size and construction, and as here illustrated, consists of a rotating shaft 20 journaled in bearings 21 in one end wall of the tub and having a crank 22 at its inner end and a link 23 connecting the crank and an upwardly extending arm 24 fixed to a bracket 25 secured to the head of the receptacle. The shaft 20 is connected to a vertically extending shaft 26 by intermeshing gears 27, 28, and the shaft 26 connected to a motor not shown, mounted on the frame 3 beneath the tub. The shafts and gears are enclosed in a casing 29. The link 23 is detachably connected to one of the parts 22, 24 and as here shown, it is detachably mounted on the crank pin 30. As here illustrated, Figs. 4 and 5, it is movable off the end of the crank pin 30 and normally held from detachment by a suitable key or locking device 31 here shown as a disk or washer having a slot 31^a therein which makes the disk a fork, the arms of 35 which slide in transverse grooves 32 in the crank pin. The fork is provided with a projection or spring pressed poppet 33 which enters a depression 34 at the bottom of one of the grooves 32 and holds the lock or fork from unintentional detachment.

The receptacle 5 is liftable out of its normal position for the purpose of elevating the same out of the water in the tub or for any other purpose as to more conveniently place the clothes in or remove them 45 from the receptacle. The mechanism by which this result is obtained comprises a rock shaft 35 journaled in the opposite end walls of the tub above and at one side of the receptacle, rock arms 36 mounted on the shaft near the end walls of the tub, the arms being connected to the upper ends of the links 12, a pedal 37 and connections between the pedal and the shaft 36. The 50 pedal 37 is pivoted to the frame 3 at 38 beneath the tub, and the connections comprise a rock arm 39 on the outer end of the shaft 35 and a link 40 connecting the pedal and the arm 39. Obviously, the receptacle can 55 be raised after the cover of the tub is removed by merely stepping on the pedal 37. Preferably, means is provided for holding the receptacle elevated, this means being here illustrated as a detent or hook 41 secured to the tub and coacting with the arm 60

39 when the arm is in its lowermost position by reason of the pedal being depressed. The tub is provided with a suitable drain outlet 42.

As the receptacle is part cylindrical it 70 may rock half way around either direction after disconnecting the link 23 from the crank 22 for the purpose of cleaning the bottom of the tub without removing the receptacle 5 therefrom. Also, the receptacle 75 5 can be completely inverted for the purpose of cleaning the outer face of the bottom thereof.

In operation, the clothes are placed in the receptacle 5 and the cleansing fluid as hot 80 water with a soapy substance therein filled in the receptacle to the water line. The motor is then started and the receptacle oscillated causing the blades 18 to alternately 85 discharge the water into the receptacle over opposite sides thereof and onto the clothes. The suction created by blades draws the water through the clothes and the perforated bottom of the tub where it is again 90 lifted by the blades 18. When this operation is completed the fluid is drained off, rinsing water filled into the tub and the operation repeated. The clothes may then be removed and wrung. The usual wringer 95 and attachments are not shown and are provided on the tub 1 and the frame therefor.

What I claim is:

1. A washing machine comprising a tub having a semi-cylindrical bottom, a clothes receptacle mounted in the tub to rock about 100 a horizontal axis concentric with the cylindrical bottom of the tub, the bottom of the receptacle having openings therein, blades projecting outwardly from near the upper edges of the bottom of the receptacle, the blades running close to the bottom of the tub and arranged to move in opposite halves of the bottom of the tub to lift the water alternately over the upper edges of 105 the receptacle and onto the clothes therein when the blades approach the limit of their throw in upward directions and to create a partial vacuum behind such blades for drawing the water downwardly through the clothes and the perforated bottom of the receptacle, substantially as and for the purpose described.

2. A washing machine comprising a tub having a cylindrical bottom, a clothes receptacle mounted in the tub to rock about a 120 horizontal axis concentric with the semi-cylindrical bottom of the receptacle, the receptacle having a substantially open top for the inlet of water, the bottom of the receptacle having openings therethrough, blades 125 projecting outwardly from near the upper edges of the bottom of the receptacle and terminating near the inner face of the bottom of the tub, and means for rocking the receptacle to cause the blades to lift the 130

water alternately over the upper edges of the receptacle and onto the clothes therein when the blades approach the limit of their throw upwardly, substantially as and for the purpose specified.

3. A washing machine comprising a tub having a cylindrical bottom, a clothes receptacle mounted in the tub to rock about a horizontal axis concentric with the semi-cylindrical bottom of the receptacle, the receptacle having a substantially open top for the inlet of water, the bottom of the receptacle having openings therethrough, blades projecting outwardly from near the upper edges of the bottom of the receptacle and terminating near the inner face of the bot-

tom of the tub, and means for rocking the receptacle to cause the blades to lift the water alternately over the upper edges of the receptacle and onto the clothes therein 20 when the blades approach the limit of their throw upwardly, the tub also having a blade arranged substantially centrally of its bottom and projecting toward and terminating at its upper edge near the bottom of the 25 clothes receptacle, substantially as and for the purpose set forth.

In testimony whereof I have hereunto signed my name, at Syracuse, in the county of Onondaga and State of New York, this 30 26th day of April, 1920.

ROBERT LELAND KINCAID.
